[57] CLAIM

The ornamental design for an electrical connector, as shown and described.

DESCRIPTION

FIG. 1 is a top perspective view of an electrical connector showing my new design, on an enlarged scale;

FIG. 2 is a top plan view thereof;

FIG. 3 is a side elevational view thereof, the opposite side being a mirror image;

FIG. 4 is an end elevational view thereof;

FIG. 5 is an opposite end elevational view thereof;

FIG. 6 is a bottom plan view thereof;

FIG. 7 is a top perspective view of a second embodiment thereof, on an enlarged scale;

FIG. 8 is a top plan view thereof;

FIG. 9 is a side elevational view thereof, the opposite side being a mirror image;

FIG. 10 is an end elevational view thereof;

FIG. 11 is an opposite end elevational view thereof;

FIG. 12 is a bottom plan view thereof.

The broken line drawing of a cable in FIGS. 1 and 7 is for illustrative purposes only and forms no part of the claimed design.
